UNITED STATES PATENT OFFICE.

JOHN G. HALL, OF NEW PROVIDENCE, PENNSYLVANIA.

WINDOW-SASH BALANCE.

No. 835,788.

Specification of Letters Patent.

Patented Nov. 13, 1906.

Application filed July 27, 1905. Serial No. 271,496.

To all whom it may concern:

Be it known that I, JOHN G. HALL, a citizen of the United States, residing at New Providence, in the county of Lancaster and State of Pennsylvania, have invented a new and useful Window-Sash Balance; and I do hereby declare the following to be a full, clear, and exact description of the invention, such as will enable others skilled in the art to 10 to which it appertains to make and use the same.

This invention relates to windows, and has for its object to provide a cordless weight for window-sashes which will hold a window-sash in any desired position and which provides means for firmly locking the weight at the desired point, which in turn locks the window.

Other and further objects and advantages 20 of the invention will be hereinafter set forth, and the novel features thereof defined by the appended claim.

My invention is illustrated in the accompanying drawings, which, with the figures of 25 reference marked thereon, form a part of this application, and in which drawings—

Figure 1 is a longitudinal section through a window-frame, showing the upper and lower sashes and the means for counterbalancing 30 and locking the same. Fig. 2 is a detail perspective fragmental view of a portion of one of the sashes and part of the frame, showing the ratchet-wheel and ratchet-bars and the locking device for the weighted member; and Fig. 3 is a sectional view through the locking 35 device.

Reference now being had to the details of the drawings by figure, 1 designates the framework of a window, having mounted 40 therein the usual lower and upper sashes 2 and 3, respectively. Mounted upon one side of the lower sash 2, as at 4, is a suitable rack-bar 5, which is adapted to engage a suitable pinion 6, which is rotatably mounted upon a pin 7, which is mounted in the framework 1. This pinion is adapted to engage a suitable rack-bar 8, which is bolted or otherwise secured to a weighted member 9, which has longitudinally-vertical movement within the 45 framework of the window 1. A plurality of perforations 10 is provided in a metallic bar 11, which is screwed or otherwise secured to the side of the weighted member 9, and adapted to engage said perforations is a suitable

50 spring-pressed pin 12, which is mounted

within the outer portion of the framework of the window. This pin 12 is provided with a suitable flange 13, which is adapted to have a spring 14 to bear against the upper surface thereof, the other end of said spring being 60 adapted to bear against the under surface of a plate 15, bolted or otherwise secured to the outside of the framework of the window. Said spring-pressed pin 12 is provided with a suitable recess 16, which is adapted to engage 65 therewith a suitable spring-pressed bolt 17, which is mounted within a suitable metallic casing, which is screwed or otherwise secured to the outside of the framework.

Mounted upon one side of the upper sash 70 3, as at 18, is a suitable rack-bar 19, which is adapted to engage a suitable pinion 20, which is rotatably mounted upon a pin 21, which is mounted in the framework 1. Said pinion is adapted to engage a suitable rack-bar 22, 75 which is bolted or otherwise secured to a weighted member 23, which has longitudinally-vertical movement within the framework of the window 1. A plurality of perforations 24 is provided in a metallic bar 25, 80 which is screwed or otherwise secured to the side of the weighted member 23, and adapted to engage said perforations is a suitable spring-pressed pin 26, which is mounted within the outer portion of the framework of 85 the window. Said pin 26 is provided with a suitable flange 27, which is adapted to have a spring 28 to bear against the upper surface thereof, the other end of said spring being adapted to bear against the under surface of a 90 plate 29, bolted or otherwise secured to the outside of the framework of the window. Said spring-pressed pin 26 is provided with a suitable recess 30, which is adapted to engage 95 therewith a suitable spring-pressed bolt 31, 100 which is mounted within a suitable metallic casing, which is screwed or otherwise secured to the outside of the framework. Thus by referring to Fig. 3 of the accompanying drawings, in connection with the detailed description of the same, as hereinbefore given, it will be readily understood how a sash is locked in any desired position.

From the foregoing it will be observed that by the provision of the apparatus shown and 105 described a simple and efficient means is provided for locking either the upper or lower sash of a window in a closed position or in any desired open position.

Having thus fully described my invention, 110

what I claim as new, and desire to secure by Letters Patent, is—

In a sash balancing and locking device, a sash-frame, a slideable sash, a rack rigidly secured thereto, a weighted sash-balancing rack-bar, a pinion arranged between and intermeshing with the teeth of both the rack and rack-bar, a perforated plate rigidly secured to said rack-bar, a locking-pin guided 5 in the sash-frame, and provided with a recess, 10

a spring tending to force the pin into engagement with the perforated plate, and a spring-actuated bolt arranged to enter the recess and hold the pin in unlocked position.

In testimony whereof I have hereto affixed 15 my signature in the presence of two witnesses.

JOHN G. HALL.
